DESIGN FOR A WORK SUIT

Ellen Hewitt Lachaud, New York, N. Y.

Application January 12, 1942, Serial No. 105,161

Term of patent 3½ years

To all whom it may concern:

Be it known that I, Ellen Hewitt Lachaud, a citizen of the United States, residing in New York city, in the Borough of Manhattan and State of New York, have invented a new, original, and ornamental Design for a Work Suit, of which the following is a specification, reference being had to the accompanying drawing, forming part thereof.

Fig. 1 is a front view of a work suit showing my design.

Fig. 2 is a rear view of the work suit shown in Fig. 1, on a reduced scale.

Fig. 3 is a fragmentary front view of the work suit shown in Fig. 1 with the belt portion turned back, and

Fig. 4 is an enlarged fragmentary view of the work suit shown in Fig. 2 in an unbuttoned position.

I claim:

The ornamental design for a work suit, substantially as shown.

ELLEN HEWITT LACHAUD.
